REFRIGERATOR

Robert T. Frazier, Chattanooga, Tenn., assignor
to Tennessee Furniture Corporation, Chattanooga, Tenn., a corporation of Tennessee

Application June 21, 1933, Serial No. 676,954

20 Claims. (Cl. 62—72)

This invention is a novel improvement in ice refrigerators of the air-conditioned type such as shown in my U. S. Letters Patent No. 1,909,261, date May 16, 1933, and the principal object of the present invention is to provide a preformed removable unit, including an electric fan and thermostat, which may be readily inserted in an opening in the ice chamber partition, whereby air in the refrigerator, between certain predetermined temperature limits may be circulated by the fan in a closed circuit through the ice chamber and food compartments in volumes inversely proportionate to the surface area of the ice, thereby maintaining a minimum low temperature evenly distributed throughout the interior of the refrigerator regardless of the size of the cake of ice, or of variations in the outside temperature.

In ice refrigerators the interior temperatures vary widely because of two main reasons: First, the temperature rises as the surface area of the cake of ice decreases; and second, the temperature varies up and down with the variations of the room temperatures. When the room temperature is rising both of these factors are operating in the same direction to accelerate the rise in temperature inside the refrigerator. In an ice refrigerator operating purely by convection there is a temperature differential within the refrigerator between the bottom and top, varying from 8° F. when the room temperature is about 70° F., up to 12—16° F. when the temperature is 100° F.

The rate of heat exchange, from ice to air, varies in direct proportion to the surface area of the ice exposed to the air and hence a 50 lb. cake of ice, and a 100 lb. cake placed side by side will require substantially the same length of time to melt in open air or in air of any given velocity, due to the fact that as the surface area of the ice is reduced a slower circulation of air in the refrigerator is produced, and the slowly moving air has a higher temperature. Therefore, temperatures of 47° to 54° F. beneath the ice chamber, and from 59° to 66° F. on the top shelf, depending upon the amount of ice in the refrigerator at the time, are quite usual. In my air-conditioned ice refrigerator this temperature deficiency is corrected by providing means for automatically controlling the speed of circulation of the air inside of the cabinet. In my novel unit the electric fan is controlled by the thermostat which is set to close the fan circuit when the temperature adjacent the thermostat is about 50° F., and to open the circuit when about 46° F. is

attained, whereby the temperature in the bottom of the refrigerator is maintained at about 42° F. substantially continuously.

I will explain the invention with reference to the accompanying drawings which illustrate several practical embodiments thereof to enable others familiar with the art to adopt and use the same; and will summarize in the claims the novel features of construction, and novel combinations of parts, for which protection is desired.

In said drawings:—

Fig. 1 is a perspective view looking upon the central partition of a three-door refrigerator from the ice chamber side.

Fig. 2 is a similar view looking from the food compartment side.

Fig. 3 is a vertical section through the refrigerator and my air-conditioning unit installed in the central partition.

Fig. 4 is a horizontal section on the line 4—4, Fig. 3.

Fig. 5 is a perspective view of the air-conditioning unit, detached, looking at the fan and thermostat mounting.

Fig. 6 is a diagrammatic section illustrating the application of my novel unit to a two-door type refrigerator, in which the ice chamber entirely covers the food compartment.

Fig. 7 is a diagrammatic section illustrating the application of my novel unit to a large type refrigerator, in which the ice chamber is disposed at the center above a milk compartment, and with food compartments disposed at both sides of the ice chamber.

The refrigerator may be of any desired type adapted to hold ice, and preferably the casing is heat insulated. In the embodiment shown in Figs. 1—5, the interior of the refrigerator contains an ice chamber A in one upper corner for holding a cake of ice B, the ice chamber being formed by the usual lining having a bottom C and central partition D, separating the ice chamber A from the main food compartment E. In the bottom C of the lining is a flue C' leading into the bottom or milk compartment F disposed immediately below ice chamber A. The partition D between the ice chamber A and food compartment E is provided with an opening D' at its top sufficiently large to snugly receive the base block of my air-conditioning unit, which block contains a flue permitting passage of air between the upper ends of the ice chamber A and food compartment E.

My novel unit preferably comprises a block 1 of wood or other material, preferably rectangular

95

100

105

110

in shape and of substantially the same area as the opening D', and of same thickness as the partition D, said block 1 having an opening 2 extending therethrough to form a flue of relatively large 5 diameter to provide an adequate passage for air circulation and for mounting the fan therein.

Block 1 is preferably covered on all sides with galvanized sheet steel, and a flange 3 preferably formed by the steel covering extends from the 10 face of block 1 exposed in the ice chamber A, which flange extends around the periphery of the block; and as the overall dimensions of block 1 were made so as to fit snugly but easily into opening D' in partition D, the block when in position 15 in the opening may be secured by four ordinary wood screws 4 passed through the flange 3 into the partition D, holding the unit securely in place. A tinned wire grid 5 is provided over opening 2, on the ice chamber side, for preventing the 20 ice B from contacting with the rotating fan blades.

At the side of block 1, opposite from the grid 5, is a metal mounting bar 7 extending diametrically across opening 2 and upon bar 7 is mounted 25 an electric motor 8 having its shaft disposed axially of opening 2; and a fan 9 is mounted upon the motor shaft, said fan being confined wholly within opening 2. A bi-metallic thermostat 10 is mounted upon an extension 7a of bar 7, and 30 the electric lead wires 11 and 12 which connect the thermostat 10 and motor 8, terminate in a plug 13.

The main electric lead wires 14 and 15 from the power terminals, which may be an ordinary 35 light socket, are preferably carried in a rubber covered cord, and enter the back of the refrigerator, and are connected to a receptacle 16 mounted in the rear wall of the refrigerator, which receptacle receives the plug 13 when the 40 unit is installed.

It is desirable that before insertion in the refrigerator the fan and thermostat be assembled in the unit, tested and adjusted, and then the unit inserted in the refrigerator and secured.

45 A porcelain baffle 17 forms a covering for partition D within the food compartment; and said baffle is formed with an inwardly extending offset portion 17a disposed opposite the block 1, and the space between offset 17a and block 1 serves 50 as a compartment G in which the fan and thermostat mechanisms of the air-conditioning unit are completely concealed. Offset portion 17a is provided with a large circular flue opening 17b in alignment with the opening 2 in block 1; and 55 a tinned wire grid 18 is placed over flue 17b so as to prevent hands, dishes, or the like from coming in contact with the fan mechanism while permitting free circulation of air therethrough. A series of openings 17c are punched in the offset 60 portion 17a along its rear edge to provide free circulation of air directly from the food compartment upon the thermostat 10 of the unit in compartment G. The above construction of the baffle 17 provides a clean, attractive, interior for 65 the food compartment, and the baffle 17 completely conceals all mechanisms of the unit.

In Fig. 6 my novel unit is shown as applied to a two-door ice refrigerator, in which the ice chamber H entirely covers the food chamber K, 70 with air passages L provided around the exterior of ice chamber H. The same fan assembly 9 previously described is inserted through the opening H' in the top of the ice chamber; and forces air down upon the ice, through flue H² 75 in the bottom of the ice chamber and into the

food compartment K, the air moving in the direction of the arrows and returning upwardly through ducts L around the exterior of the ice chamber and back to the fan unit 9.

As shown in Fig. 7 my novel unit is applied to a large refrigerator of about twenty-five or thirty cubic feet, in which the ice chamber M is in the center above a milk compartment N, and food chambers P, Q, are disposed at the sides of the ice chamber. The fan unit 9 and the path of 80 circulated air as indicated by the arrows in Fig. 7, is substantially identical with that above described regarding Fig. 6.

The electric fan 9 forces the warmer air at the upper end of the food compartment E 90 through flues 17b and 2 and down upon the ice B in ice chamber A; and downwardly through the flue C' in the bottom of the ice chamber into the milk compartment F, the chilled air circulating through chambers F and E in the direction of the arrows and back again to the ice chamber A, the forced circulation maintaining the temperatures in the compartments A, F and E substantially the same.

The fan 9 is controlled by thermostat 10 preferably adjusted to close the fan circuit when a temperature of 50° F. is reached in the top of the food chamber E and to open the circuit at 45° F. The fan 9 in practice is found to operate about five minutes and remain idle about twenty-five 100 minutes when the room temperature is constantly at 80° F.; and the motor 8 being less than 1/20th of horse-power, consumes less current than an ordinary 40 watt light bulb, and develops very 105 short heat in the refrigerator due to the extremely short cycle of operation required.

Actual tests have shown that, with a thermostatically operated fan in the refrigerator, the increase in ice consumption in the cheaper board type insulated ice box of 100 pounds capacity was 115 only 6 pounds per 24 hours, and I was able to maintain the temperature between 46° and 50° F. in the warmest part of the refrigerator continuously up until the time there was only 10 pounds of ice left in the box. The same refrigerator 120 without the fan in it showed a temperature in the warmest part of 63° when there were still 44 pounds of ice in the refrigerator. My invention therefore provides novel and useful features in 125 ice refrigerators, as it offers low temperature and economical refrigeration to those who cannot afford electric refrigerators, as well as to those who prefer ice refrigerators because of their obvious advantages.

I claim:—

1. In a refrigerator having an ice chamber and a food compartment and having flues connecting the chamber and compartment; and a removable air circulating unit in the flue adapted to circulate air through the chamber and compartment, said unit including automatic regulating means for circulating the air in volumes inversely proportional to the surface area of the ice in the chamber.

2. In a refrigerator as set forth in claim 1, 140 said unit comprising a base; a rotatable fan carried by said base; and a thermostat on the base adapted to control said fan.

3. In a refrigerator as set forth in claim 1, said unit comprising a block adapted to fit said flue 145 and having an opening therethrough; an electric fan mounted on said block coaxial with the opening; a thermostat mounted on the block; and electrical connections between the fan and thermostat.

4. In a refrigerator as set forth in claim 1, an electric socket within the refrigerator; said unit comprising a block adapted to fit said flue and having an opening therethrough; an electric fan 5 mounted on said block coaxial with the opening; a thermostat mounted on the block; an electrical circuit including the fan and thermostat; and a plug in the circuit adapted to engage the socket.
5. In a refrigerator having an ice chamber and 10 a food compartment and having flues connecting the ice chamber and compartment; and a removable air circulating unit in the flue adapted to circulate air through the chamber and compartment, said unit including automatically controlling means for circulating the air within predetermined temperature limits.
6. In a refrigerator as set forth in claim 5, 15 said unit comprising a base; an electric fan on said base; and a thermostat in circuit with said fan.
7. In a refrigerator as set forth in claim 5, said unit comprising a block adapted to fit said flue and having an opening therethrough; an electric fan mounted on said block coaxial with the opening; a thermostat mounted on the block; and an electrical circuit including the fan and thermostat.
8. In a refrigerator as set forth in claim 5, an 20 electric socket within the refrigerator; said unit comprising a block adapted to fit said flue and having an opening therethrough; an electric fan mounted coaxial with the opening; a thermostat mounted on the block; and an electrical circuit including the fan and thermostat.
9. In a refrigerator having an ice chamber a 25 food compartment, flues connecting the chamber and compartment; an opening through the ice chamber into the food compartment; and a removable fan and thermostat unit mounted in said opening adapted to circulate a volume of air through the chamber and compartment in inverse proportion to the surface area of the ice in the chamber.
10. In a refrigerator as set forth in claim 9, said 30 unit comprising a member adapted to fit said opening, and carrying said fan and thermostat.
11. In a refrigerator as set forth in claim 9, said unit comprising a block adapted to fit said opening; said block having a passage therethrough; said fan being mounted coaxial with the passage; said thermostat being mounted on the block; and an electrical circuit including the fan and thermostat.
12. In a refrigerator as set forth in claim 9, an 35 electric socket within the refrigerator; and said unit comprising a block adapted to fit said opening and having a passage therethrough; said fan being mounted within said passage; said thermostat being mounted on the block; an electrical circuit including the fan and thermostat; and a plug in the circuit adapted to engage the socket.
13. In a refrigerator having an ice chamber in the upper portion and having a food compartment 40 below or to one side of the ice chamber, and having flues connecting the chamber and compartment; an opening at the upper end of the ice chamber into the food compartment; an air circulating unit removably mounted in said opening adapted to circulate a volume of air through the chamber and compartment in inverse proportion to the surface area of the ice, a baffle plate in the food compartment, the space between the
- baffle plate and ice chamber forming a housing for the unit; and said flue having an opening therethrough opposite the opening in the ice chamber.
14. In a refrigerator having an ice chamber in the upper portion and having a food compartment below or to one side of the ice chamber, and having flues connecting the chamber and compartment; an opening at the upper end of the ice chamber into the food compartment; an air circulating unit removably mounted in said opening adapted to circulate a volume of air through the chamber and compartment in inverse proportion to the surface area of the ice, a baffle plate in the food compartment having an inwardly offset portion opposite the opening in the ice chamber, the space between the offset portion of the baffle plate and ice chamber forming a housing for the unit; and said offset portion having an opening therethrough opposite the opening in the ice chamber. 80
15. In a refrigerator as set forth in claim 14, said unit comprising a block adapted to fit said opening, an electric fan on said block; and a thermostat on the block adapted to control said fan; and said baffle plate having a series of openings therethrough in way of the thermostat. 85
16. An air-conditioning unit for refrigerators comprising a base; an electric fan mounted on said base, a thermostat mounted on the base; and an electrical circuit including the fan and thermostat. 90
17. An air-conditioning unit for refrigerators comprising a block having an opening therethrough; an electric fan mounted coaxial with the opening; a thermostat mounted on the block; and an electrical circuit including the fan and thermostat; and a plug in the circuit adapted to engage an electric power socket. 95
18. An air-conditioning unit for refrigerators comprising a block adapted to fit a refrigerator flue; means for locking the block in the flue; said block having an opening therethrough; an electric fan mounted coaxial with the opening; a thermostat mounted on the block; and an electrical circuit including the fan and thermostat; and a plug in the circuit adapted to engage an electric power socket. 100
19. An air-conditioning unit for refrigerators comprising a block adapted to fit a refrigerator flue; said block having an opening therethrough; a mounting bar on the block extending across the opening; an electric fan mounted on said bar and housed within the opening; a thermostat mounted on the bar; and an electrical circuit including the fan and thermostat; and a plug in the circuit adapted to engage an electric power socket. 110
20. An air-conditioning unit for refrigerators comprising a block adapted to fit a refrigerator flue; a locking flange around said block; said block having an opening therethrough; a mounting bar on the block extending across the opening; an electric motor mounted on said bar with its shaft coaxial with the opening; a fan blade mounted on the motor shaft within the opening; a thermostat mounted on the bar; and an electrical circuit including the motor and thermostat; and a plug in the circuit adapted to engage an electric power socket. 120
